UNITED STATES PATENT OFFICE.

BERNHARD KRÄMER, OF CHARLOTTENBURG, GERMANY, ASSIGNOR TO GENERAL ELECTRIC COMPANY, A CORPORATION OF NEW YORK.

INTERNAL-COMBUSTION ENGINE.

1,171,855.

Specification of Letters Patent. Patented Feb. 15, 1916.

Application filed November 25, 1913. Serial No. 802,914.

To all whom it may concern:

Be it known that I, BERNHARD KRÄMER, a subject of the Emperor of Germany, residing at Charlottenburg, Germany, have 5 invented certain new and useful Improvements in Internal-Combustion Engines, of which the following is a specification.

In the manufacture of internal combustion engines it frequently happens that the 10 constructor is called upon to furnish engines for different outputs having different numbers of cylinders. This can readily be done by keeping, in addition to a stock of cylinders, etc., a stock of main shafts having 15 different numbers of cranks. This, however, is objectionable in most instances on account of the expense. It has been proposed to avoid this by making a relatively short shaft section having two journals for 20 each cylinder and assembling them with two end bearings for each section with a coupling located between each two adjacent bearings. This arrangement, while practical in many instances, is objectionable for 25 the reason that it increases the length of each shaft section, the number of bearings, and because it makes it more difficult to obtain the proper alinement of the parts. It also increases the total length of the engine 30 and hence further increases the cost.

My invention has for its object to overcome the objections above noted by making the shaft sections in a peculiar manner, each with one journal, so that when assembled 35 a single bearing suffices for each shaft section. For a consideration of what I believe to be novel and my invention, attention is directed to the accompanying description and claims appended thereto.

40 The accompanying drawing illustrates a two-cylinder engine in vertical section made in accordance with my invention.

1 indicates the main frame of the engine, which in the present case, also forms a receiver 2 for supplying pure air to the cylinders for the purpose of cleaning them of the exhaust gases between firing strokes and also for supplying the necessary air to support combustion.

50 3 and 4 indicate working cylinders of any suitable construction of which as many may be provided as are necessary. In one end of the receiver is the cylinder 5 of an air pump, and located therein is a piston 6. I 55 have omitted the valve mechanism of the

pump and working cylinders in the interest of clearness and simplicity, but it is to be understood that such mechanism will be provided. Each working cylinder has a pair of pistons 3^a and 4^a respectively that 60 move toward each other on the compression stroke and away from each other on the firing stroke. Each upper or outer piston is provided with a cross-head 7 that is connected by side rods 8 with cranks on the 65 main shaft. Each lower or inner piston is connected to a crank on the main shaft by a connecting rod 9.

The main shaft is divided into sections, each section corresponding to one cylinder 70 so that the number of cylinders can be increased or decreased at will. Each section is provided with one journal 10 and three cranks and pins 11, 12 and 13 that pass through the connecting rods. On the journal end of the section is a disk or face plate 14 that, in addition to forming a part of a journal, also forms a part of a coupling for uniting said shaft section with the adjacent shaft section. The other end of the crank 80 section is provided with a disk or face plate 15 that also forms a part of a coupling as well as a part of a crank. In other words, each crank shaft section is provided with three cranks and a single journal, the end 85 portions of the outer crank and the journal forming coupling disks that are complementary to similar disks on adjacent crank shaft sections. Each journal is supported by a bearing 16, there being one bearing for 90 each crank section. In this manner I avoid making the engine unduly long. The crank shaft section which drives the compressor or fresh air pump is provided with a journal 17 having a disk 18 on one side of the bearing 19 and a disk 20 and crank pin 21 on the other side, said pin being united with the connecting rod 22. In such a construction the receiver will, of course, be of the proper length and construction to receive all of the 95 cylinders. The base of the engine supporting the bearings etc. has been omitted in the interest of clearness, but it is understood that it may be of any suitable or well known construction.

100 It is evident in assembling such an engine that for one reason or another the crank shaft sections and the cylinders may not properly aline, measured in an axial direction. If such is the fact this may be com- 110

pensated for by inserting one or more disks 23 of suitable thickness between adjacent disks. After being properly aligned said disks are clamped together by bolts or other means in any suitable manner. It will be seen that for each working cylinder and each pump cylinder there is but one bearing. In other words, the engine in the present illustration has two working cylinders 12 and the number of main bearings corresponds thereto. If another cylinder is added there will be added, of course, another crank shaft section, the end of which is shown, and one bearing. This duplication may be made 15 at will.

In accordance with the provisions of the patent statutes, I have described the principle of operation of my invention, together with the apparatus which I now consider 20 to represent the best embodiment thereof; but I desire to have it understood that the apparatus shown is only illustrative, and that the invention can be carried out by other means.

25 What I claim as new and desire to secure by Letters Patent of the United States, is:—

1. In an engine, the combination of a plurality of cylinders, a support therefor, a pair of pistons for each cylinder, connecting

30 rods for the pistons, a main crank shaft connected to the rods and divided into as many sections as there are working cylinders, each shaft section comprising a plurality of integrally formed cranks, a single journal, and integrally formed face plates at the ends 35 which act as couplings, and a bearing for each of said journals.

2. In an engine, the combination of a plurality of cylinders, a support therefor, a 40 pair of pistons for each cylinder, connecting rods for the pistons, a main crank shaft connected to the rods and divided into as many sections as there are working cylinders, each shaft section comprising a crank at one end, a journal at the other end, and two intermediate cranks, with face plates carried by 45 and formed integrally with the journal and the end crank to serve as couplings to unite the sections, thin disks between the face plates to align the shaft sections with the 50 cylinders, and a bearing for each of the journals.

In witness whereof, I have hereunto set my hand this 27th day of October, 1913.

BERNHARD KRÄMER.
